UNITED STATES PATENT OFFICE

EDWARD ARTHUR FORBES, OF WEST PALM BEACH, FLORIDA

SEA WALL

Application filed May 22, 1930. Serial No. 454,737.

The present invention has relation to means for preventing encroachment of the sea and maintaining a predetermined shore line, particularly when the ground adjacent to the beach is occupied by buildings.

The invention provides a wall which is stable, lasting, and capable of resisting the scouring action of the waves and currents, and which may be constructed at an outlay less than involved in forming the usual step and roll way type of sea wall of concrete.

The invention primarily relates to the foundation for sustaining the superstructure of concrete, and which foundation extends to a depth to prevent undermining or wash out, and which is adapted to localize any possible damage and minimize the cost of repairs.

In accordance with the invention, the foundation includes a bulkhead and buttresses interlocked therewith, ties bracingly connecting the parts, and a filling of earth, sand or other suitable material conveniently at hand. The bulkhead and buttresses comprise sheet metal piling driven to a suitable depth of about fifteen to thirty feet, more or less, according to location and conditions. The concrete superstructure is built upon this foundation and interlocked therewith to form a unit, all as will appear more fully hereinafter.

While the drawings illustrate a preferred embodiment of the invention, it is to be understood that in adapting the means to meet specific needs and requirements, the design may be varied and changes in the minor details of construction may be resorted to within the scope of the invention as claimed, without departing from the spirit thereof.

For a full understanding of the invention and the merits thereof, reference is to be had to the following description and the drawings hereto attached, in which:

Figure 1 is a perspective view of a section of sea wall embodying the invention.

Figure 2 is an enlarged cross sectional view on the line 2-2 of Figure 1.

Figure 3 is a top plan view of the bulkhead and buttress piling and connecting ties forming the frame work of the foundation.

Figure 4 is a transverse sectional view on the line 4-4 of Figure 3.

Figure 5 is a fragmentary perspective view showing the ties applied to the sheet metal piling.

Figure 6 is a fragmentary perspective view of angularly disposed piles and the angle bar forming connecting means therebetween.

Corresponding and like parts are referred to in the following description and designated in the several views of the drawings by like reference characters.

In accordance with the present invention, the sea wall comprises a concrete superstructure of the step and roll way type and a foundation of sheet metal piling, and a filling, the piling being driven to a depth to insure stability of structure under all conditions and prevent undermining by the scouring action of waves and currents. The top of the piling is embedded and anchored in the superstructure. The piling paralleling the shore line and beach is designated as the bulkhead piling, whereas that disposed shoreward and at a right angle thereto is designated as the buttress piling, and the bulkhead and buttress piling are bounded and tied by metal rods, the space thus enclosed being filled with sand, earth or other material, thus forming a foundation, which is stable and not liable to be undermined by the action of currents and waves.

In accordance with the invention, a line of sheet metal piling 1 is driven into the earth along the prescribed line which usually parallels the shore. Other sheet metal piling 2 is driven into the earth shoreward of the piling 1 and preferably at a right angle thereto. The piling 1 corresponds to the bulkhead and the piling 2 to the buttresses, the bulkhead piling and the buttress piling being securely joined to prevent possible separation. The piling may be of any construction and the individual elements or members are interlocked to form a continuous structure. The buttress piling 2 may be connected to the bulkhead piling 1 in any substantial manner and, as indicated most clearly in Figure 6 of the drawings, an angle iron 3 is utilized and riveted or otherwise secured to the ad-

ja⁵cent piles. The piling is driven to a safe depth usually twenty to thirty feet below the median water line, to prevent any possible wash out. The buttress piling 2 may extend shoreward any determinate distance and may be spaced apart a distance depending upon the resistance to be offered to the action of waves and currents. After the piling has been driven, longitudinal tie rods 4 are passed through openings formed in the bulkhead piling 1 and other rods 5 are arranged vertically between the piling and the longitudinal rods 4. The openings receiving the longitudinal rods 4 are formed in the piling 15 after the latter has been driven and an acetylene torch is generally employed for removing the metal to form the openings. The longitudinal rods 4 and the vertical rods 5 are disposed upon the side of the piling facing the sea and provide means for securely anchoring the facing 6 of the bulkhead. Other rods 7 are passed through openings formed in the buttress piling 2 adjacent the upper ends thereof. Transverse rods 8 are placed upon the longitudinal rods 7 and are connected to the upper ends of the piling 1. The rods 7 and 8 form ties for bracingly connecting the buttress and bulkhead piling and also reinforce the superstructure and provide a bond between said superstructure and the foundation. After the piling has been driven, the space in the rear of the bulkhead and between the buttress piling is filled in with sand, earth or other material, to approximately the top of the piling, after which the superstructure is placed in position upon the piling. It is observed that the top portion of the piling and the rods 7 and 8 are exposed to admit of the concrete forming the superstructure obtaining a substantial and firm bond with the piling of the foundation. The rods 7 and 8 becoming embedded in the structure, reinforce and strengthen the same and the concrete, in turn, unites the rods 7 and 45 8 in a manner to form a unitary structure which is tied, braced and reinforced, with the result that any possible damage is localized and the structure as a whole rendered stable and resistant to the scouring action of waves and currents.

The superstructure is of the step and roll way type of sea wall and comprises steps 9, roll way 10 and reinforcements 11. The superstructure is reinforced and strengthened 55 in the accustomed way by rods embedded therein and is further strengthened and reinforced by the embedded rods 7 and 8 and the upper ends of the piling 1 and 2.

A sea wall of the step and roll way type as generally constructed is expensive because the superstructure and foundation are of one-piece structure consisting of concrete, and to extend the same to a depth to resist the scouring action of waves and currents has not been practicable. In accordance with the present

invention, the superstructure alone is of concrete and the foundation of sheet metal piling and filling, and, as a result, the wall may be constructed at a materially less cost and the foundation may penetrate to a depth to preclude any possible scouring action by waves or currents. Moreover, the wall is rigid and possesses permanent stability and provides a bearing power for localizing any possible damage and admitting of any necessary repairs being cheaply and readily effected. The foundation piling and the concrete superstructure are firmly bonded and the permanency of the superstructure is maintained because of the depth of penetration of the piling, the filling acting in the capacity of ballast.

What is claimed is:

1. A sea wall comprising sheet metal piling interlocked and driven to a depth to insure permanency and stability and forming a bulkhead, transverse sheet metal piling permanently and rigidly connected to the bulkhead piling and extending shoreward and driven to a depth to insure a rigid and stable structure, longitudinal and transverse rods engaging the upper portions of the piling, and a concrete superstructure supported upon the piling and reinforced and strengthened by the said longitudinal and transverse rods which are embedded therein and bonded thereby. 85
2. A sea wall comprising interlocked sheet metal piling forming a bulkhead, interlocked transverse piling forming buttresses and permanently connected to the bulkhead piling, a facing of concrete applied to the bulkhead piling, tie rods connecting the upper ends of the bulkhead and buttress piling, and a superstructure of concrete supported upon the piling and forming a bond for the longitudinal and transverse rods which are embedded therein, said superstructure connecting with the said facing. 90

3. A sea wall of the step and roll way type comprising a line of interlocking sheet metal piling forming a bulkhead, lines of interlocking sheet metal piling having a transverse arrangement and permanently and rigidly connected to the bulkhead piling to form buttresses, longitudinal and vertical rods applied to the outer side of the bulkhead piling, longitudinal and transverse rods engaging the upper ends of the bulkhead and buttress piling, a facing of concrete applied to the bulkhead piling, a filling occupying the space between the bulkhead and buttress piling, and a superstructure of concrete supported upon the piling and filling and having the upper ends of the piling and the longitudinal and transverse rods embedded therein and bonded thereby. 110

4. A sea wall of the step and roll way type which consists of sheet metal piling driven substantially parallel with the shore line, a sheet metal piling shoreward of the shore line 130

piling driven at substantially a right angle to the shore line piling and rigidly secured thereto, longitudinal rods passed through openings in the shore line piling, vertical rods disposed across the longitudinal rods, longitudinal and transverse rods connected to the upper ends of the piling, a filler for the piling, a concrete foundation uniting with the top portion of the piling and forming a bond for the longitudinal and transverse rods, and a facing of concrete applied to the upper portion of the shore line piling.

In testimony whereof I affix my signature.

EDWARD ARTHUR FORBES.
